UNITED STATES PATENT OFFICE.

FRED H. WINTER, OF SCHENECTADY, NEW YORK, ASSIGNOR TO GENERAL ELECTRIC COMPANY, A CORPORATION OF NEW YORK.

CONTACT-MAKING VOLTMETER.

1,267,156.

Specification of Letter's Patent. Patented May 21, 1918.

Application filed March 1, 1917. Serial No. 151,717.

To all whom it may concern:

Be it known that I, FRED H. WINTER, a citizen of the United States, residing at Schenectady, county of Schenectady, State of New York, have invented certain new and useful Improvements in Contact-Making Voltmeters, of which the following is a specification.

My invention relates to contact making meters, and more especially to contact making voltmeters in which electromagnetic holding means are employed to prevent chattering of the contacts.

In the use of motor driven feeder regulators of the induction type, the operation of the motor is controlled by means of a special form of control device commonly known as a contact making voltmeter. Variations in voltage on the feeders cause the voltmeter to close one or the other of two circuits and thereby effect the rotation of the motor, and hence of the movable element of the induction regulator, in one direction or the other so as to restore the feeder voltage to the desired value. When the movable contact member of the voltmeter engages one of the stationary contacts in response to a change in feeder voltage, it is desired that such contact be maintained until a certain appreciable correction has been effected in the feeder voltage in order to prevent objectionable chattering of said contacts. To this end it has heretofore been proposed to employ electromagnetic holding means which become effective upon the engagement of the movable contact member with a stationary contact member to hold the former in engagement with the latter until a predetermined change in the feeder voltage is effected. Where the control circuits, by which I mean the circuits through which the control of the motor is effected and from which the electromagnetic holding means are energized, are supplied with energy from the same source as the feeder circuit, the voltage of which is to be regulated, the arrangement to which brief reference has been made operates satisfactorily. In some installations, however, it is desirable to supply the said control circuits from a source of energy other than that from which the feeder circuits are supplied, and in this event it is possible and quite probable that the frequency of the voltage in the supply circuits

will differ from that in the feeders or that said voltages will be out of synchronism. In contact voltmeters of the kind under consideration, it is customary and practically necessary to locate the holding means and the winding which actuates the movable contact member close to one another. It therefore results that the magnetic field of one overlaps the magnetic field of the other. In case the voltage of the control circuits has the same frequency as, and is in synchronism with, the voltage of the feeders, the magnetic interference is of little moment, since this difference may be taken into consideration in designing the various windings. If, however, the voltage of the control circuits has a different frequency than the voltage of the feeder, the magnetic interference becomes troublesome since it results in a fluctuation, above and below the desired value, in the holding effect of said electromagnetic holding means. If the voltage of the supply circuits is out of synchronism with, but has the same frequency as, the voltage of the feeder, the holding effect of said electromagnetic holding means is less than when the two voltages are in synchronism.

It is the object of my invention to provide means in a contact making meter of the type above referred to whereby the difficulties, heretofore met with when the controlling circuits are supplied with energy from a source other than that to which the feeders are connected, are avoided.

Although my invention is useful in any relation where a device is under the joint control of electromagnetic means connected to separate alternating current sources, nevertheless, in the accompanying drawing I have elected to illustrate my invention as applied to a contact making voltmeter which is adapted to control the operation of a feeder regulator of the induction type.

In said drawing, Figure 1 is a diagrammatic view showing the essential parts of my contact making voltmeter, together with connections adapting the same to the control of an induction regulator, and Fig. 2 is a view of a modification showing a different arrangement of the windings of the contact making voltmeter.

Referring to Fig. 1, the feeder 1 is shown as connected to an induction regulator 2 of the usual type, which is adapted to be oper-

ated by a motor 3. The motor is controlled by the contact making voltmeter 4 which comprises stationary contacts 5 and 6, a movable contact member 7 adapted to coöperate with said stationary contact, and a movable core 8, attached to said movable contact member and adapted to be actuated by a winding 9, which is connected through a variable resistance 10 to the secondary of a potential transformer 11, the primary of which is connected to the feeder 1.

The contact making voltmeter is also provided with the electromagnets 12 and 13, which are adapted, when the movable contact member 7 engages with the stationary contacts 5 and 6 respectively, to hold said movable contact member in engagement therewith. The winding of the electromagnet 12 is connected to the stationary contact 5 and, through a resistance 14, to one phase 15 of a three-phase circuit. The winding of the electromagnet 13 is connected through a winding 16, which coöperates with the movable core, 8 to the stationary contact 6 and, through a resistance 17, to another phase 18 of said three-phase circuit. The movable contact member 7 is connected to a third phase 19 of said three-phase circuit. The winding 16 and the winding of the electromagnet 13 are wound oppositely with respect to the flux developed by winding 9.

A low voltage relay 20, the winding of which is connected across the secondary of the transformer 11, is adapted, upon a sufficient reduction in the feeder voltage, to disengage the movable contact member 21, which is electrically connected to stationary contact 5, from the stationary contact 22, with which it normally engages and cause it to engage with stationary contact 23.

The motor 3, which may be a three-phase induction motor, is supplied with energy from the phases 15, 18 and 19 of a three-phase circuit, the connections of the first two of which to the motor are adapted to be reversed by the switch 24 and the connection of the last one of which to the motor is permanent. The reversing switch 24 is adapted to be operated by the electromagnets 25 and 26, which have movable cores connected to said switch. Upon reversing the connections of the phases 15 and 18 to the induction motor 3 a reversal in the direction of rotation of said motor results.

One terminal of the winding of the electromagnet 25 is connected both to the stationary contact 6 and to the stationary contact 23, whereas the other terminal is connected to the phase 18. One terminal of the winding of the electromagnet 26 is connected to the stationary contact 22, whereas the other terminal is connected to the phase 15.

The contact making voltmeter, illustrated in Fig. 2, is in most respects like that illus-

trated in Fig. 1, as is indicated by the use of like reference numbers to indicate corresponding elements in the two figures, except that the auxiliary winding 16 and the winding of electromagnet 13 are adapted to be connected in parallel, rather than in series, upon the engagement of movable contact 7 with contact 6.

The operation of the system, to which my invention is applied, is understood to be as follows: Upon the feeder voltage decreasing below the desired value, the movable contact member 7 will be caused to engage with stationary contact 5 whereupon parallel circuits are established, one of which extends from the movable contact member 7, which is, as previously indicated, permanently connected to the phase 19, through the winding of the electromagnet 12 and the resistance 14 to the phase 15, and the other of which extends from the movable contact member 7 through the movable contact member 21, stationary contact 22 and the winding of the electromagnet 26 to the phase 15. The electromagnets 12 and 26 are therefore simultaneously energized, the former exerting a holding effect upon the movable contact member 7, and the latter effecting the movement of the switch 24 to the right-hand position thereof, whereupon a rotation of the motor 3 in a direction to increase the feeder voltage results.

In a similar manner, if the feeder voltage is above the predetermined value, the movable contact member 7 will be caused to engage with the stationary contact 6 whereupon two circuits are established, one of which extends from the movable contact member 7 through winding 16 and the winding of the electromagnet 13, connected in series, in case the arrangement illustrated in Fig. 1 obtains, or in multiple in case the arrangement illustrated in Fig. 2 obtains, and the resistance 17 to the phase 18, and the other of which extends from said movable contact 7 through the winding of electromagnet 25 to the phase 18. The electromagnets 13 and 25 are therefore simultaneously energized, the former exerting a holding effect upon the movable contact member 7, and the latter effecting the movement of the switch 24 to the left-hand position thereof, whereupon a rotation of the motor 3 in a direction to decrease the feeder voltage results.

With special reference to the function of my invention which involves the use of the winding 16, let it be assumed that the movable contact 7 is in engagement with contact 6 and, for purposes of explanation, that the voltage in the control circuits, including the windings of electromagnets 12 and 13, and the winding 16, has a different frequency than that of the feeder circuit. If this be the case, and the winding 16 be not em-

ployed, the flux or magnetomotive force developed by the winding 9 will alternately cause an increase or decrease in the holding effect of electromagnet 13, since the electromagnet 13 is located within the magnetic field set up by said winding 9. If the voltage in the control circuits be out of synchronism with that of the feeder, but have the same frequency, the holding effect of the electromagnet 13 will be less than when said voltages are in synchronism. To compensate for the variations in the holding effect of electromagnet 13, the winding 16 is employed. This winding 16, according to the drawing, is located adjacent the winding 9 and is wound oppositely, with respect to the flux developed by winding 9, to the winding of electromagnet 13. If the magnetomotive force of winding 9 be in a direction to oppose that of the winding of the electromagnet 13, which may be assumed to be the condition when the voltages impressed upon said windings are 180 degrees out of phase, the magnetomotive force of winding 16 will be in the same direction as that of winding 9 and hence the force tending to lift the core 8 will be increased by an amount sufficient to compensate for the decreased holding effect of electromagnet 13. Similarly if the magnetomotive force of winding 9 be in a direction to assist that of the winding of the electromagnet 13, which may be assumed to be the condition when the voltages impressed upon the said windings are in phase, the magnetomotive force of winding 16 will oppose that of winding 9 and hence the force tending to lift the core 8 will be decreased, by reason of such opposition, by an amount sufficient to compensate for the increased holding effect of the electromagnet 13. Furthermore in the modification illustrated in Fig. 1, in which the windings 16 and the winding of electromagnet 13 are in series, the electromotive forces induced in said windings will oppose each other by reason of the fact that, as previously mentioned, said windings are oppositely wound with respect to the flux set up by the winding 9 and hence the circuit including the winding of electromagnet 13 is rendered non-inductive, to any desired degree, with respect to the winding 9.

The magnetic field set up by winding 9 also produces an effect on the winding of the electromagnet 12, but this is not objectionable since the winding of electromagnet 12 and winding 9 are so related to each other and to the movable member 7 that when the holding effect of electromagnet 12 is weakened there is a reciprocal action tending to weaken the effect of winding 9, and when the holding effect of electromagnet 12 is increased the effect of winding 9 likewise increases.

A low voltage relay 20, which operates,

upon an abnormal decrease in the feeder voltage, to electrically connect the stationary contact 5 with the stationary contact 23 and hence to energize the electromagnet 25 to move the switch 24 into the position illustrated and thus to cause a rotation of the induction motor 3 in a direction to reduce the feeder voltage, is provided to prevent an adjustment of the regulator to decrease the feeder voltage upon an abnormal decrease thereof.

I conceive that various modifications of my invention may be made and I accordingly do not desire to be limited to the exact arrangement shown, but seek to cover in the appended claims all such modifications and arrangements as fall within the scope and spirit of my invention.

What I claim as new and desire to secure by Letters Patent of the United States, is,—

1. In an alternating current contact making meter, the combination of a stationary contact, a movable contact adapted to co-operate therewith, electro-responsive means for actuating said movable contact, a winding adapted to be energized upon the engagement of said movable contact with said stationary contact and tending, when energized, to maintain such engagement, and means adapted to compensate for the magnetic interference between said electro-responsive means and said winding.

2. In an alternating current contact making meter, the combination of a stationary contact, a movable contact adapted to co-operate therewith, electro-responsive means for actuating said movable contact, and a plurality of windings adapted to be energized upon the engagement of said movable contact with said stationary contact, one of said windings tending, when energized, to maintain the engagement between said movable contact and said stationary contact and another of said windings tending, when energized, to compensate for the magnetic interference between said electro-responsive means and the first mentioned winding.

3. In an alternating current contact making meter, the combination of a plurality of stationary contacts, a movable contact adapted to co-operate therewith, electro-responsive means for effecting the operation of said movable contact, a winding adapted to be energized upon the engagement of said movable contact with one of said stationary contacts and tending, when energized, to maintain such engagement, and a plurality of windings adapted to be energized upon the engagement of said movable contact with another of said stationary contacts, one of said last mentioned windings tending, when energized, to maintain engagement between said movable contact and said last mentioned stationary contact and the other of said windings tending, when energized,

- to compensate for the magnetic interference between said electro-responsive means and the other of the last mentioned windings.
4. The combination with a plurality of 5 alternating current circuits of a contact making meter comprising a stationary contact, a movable contact adapted to coöperate therewith, electro-responsive means, responsive to an electrical condition in one of said circuits, 10 for effecting the operation of said movable contact, a winding coöperating with said electro-responsive means and adapted to be energized for another of said circuits upon the engagement of said movable contact 15 with said stationary contact, and electro-magnetic means adapted to be energized from the last mentioned circuit upon the engagement of said movable contact with said stationary contact and tending, when energized, to maintain such engagement, said winding and said electro-magnetic means being so related as to compensate for the magnetic interference between said electro-responsive means and said winding.
- 20 5. The combination with a plurality of alternating current circuits of a contact making meter comprising a stationary contact, a movable contact adapted to coöperate therewith, electro-responsive means, responsive to an electrical condition in one of said circuits, for effecting the operation of said movable contact, a winding coöperating with said electro-responsive means and adapted to be energized from another of said circuits 25 upon the engagement of said movable contact with said stationary contact, and electro-magnetic means comprising a winding adapted to be energized from the last mentioned circuit upon the engagement of said 30 movable contact with said stationary contact and tending, when energized, to maintain such engagement, said windings being oppositely wound with respect to the direction of the magnetic field developed by said electro-responsive means.
- 35 6. The combination with a plurality of alternating current circuits of a contact making meter comprising a stationary contact, a movable contact adapted to coöperate therewith, electro-responsive means, responsive to an electrical condition in one of said circuits, for actuating said movable contact, a plurality of windings oppositely wound with respect to the direction of the 40 magnetic field developed by said electro-responsive means and adapted to be serially connected to another of said circuits upon the engagement of said movable contact with said stationary contact, one of said 45 windings tending, when so connected, to maintain engagement between said movable contact and said stationary contact and another of said windings coöperating with and adapted to modify the action of said electro-

7. The combination with a feeder circuit and an induction type regulator therefor, of a reversible motor for adjusting the position of the movable element of said regulator and thereby adjusting the voltage on 70 said feeder circuit, an alternating current supply circuit for said motor independent of said feeder circuit, electromagnetic reversing means for said motor, and a contact making voltmeter adapted to control said electromagnetic reversing means, said contact making voltmeter comprising stationary contacts, a movable contact adapted to coöperate therewith, electro-responsive means, responsive to a decrease in feeder voltage, for effecting 75 the engagement of said movable contact with one of said stationary contacts and, to an increase in feeder voltage, for effecting the engagement of said movable contact with another of said stationary contacts, a winding adapted to be connected to said independent alternating current supply circuit upon the engagement of said movable contact with the first mentioned stationary contact and tending, when so connected, to 80 maintain such engagement, and a plurality of windings oppositely wound with respect to the direction of the magnetic field set up by said electro-responsive means and adapted to be serially connected to said independent alternating current supply circuit upon the engagement of said movable contact with the second mentioned stationary contact, one of said windings tending, when so connected, to maintain engagement between said movable contact and the second mentioned stationary contact and the other of said windings coöperating with and adapted to modify 85 the action of said electro-responsive means.
8. The combination with a feeder circuit 90 and an induction type regulator therefor, of a reversible motor for adjusting the position of the movable element of said regulator and thereby adjusting the voltage on said feeder circuit, an alternating current supply circuit for said motor independent of said feeder circuit, electromagnetic reversing means for said motor, a contact making voltmeter adapted to control said 95 electromagnetic reversing means, said contact making voltmeter comprising stationary contacts, a movable contact adapted to coöperate therewith, electro-responsive means, responsive to a decrease in feeder voltage, for effecting the engagement of said movable 100 contact with one of said stationary contacts and, to an increase in feeder voltage, for effecting the engagement of said movable contact with another of said stationary contacts, a winding adapted to be connected to 105 said independent alternating current supply circuit upon the engagement of said movable contact with the first mentioned stationary contact and tending, when so connected, to maintain such engagement, and a plurality 110 of windings oppositely wound with respect to the direction of the magnetic field developed by said electro-responsive means and adapted to be serially connected to said independent alternating current supply circuit upon the engagement of said movable contact with the second mentioned stationary contact, one of said windings tending, when so connected, to maintain engagement between said movable contact and the second mentioned stationary contact and the other of said windings coöperating with and adapted to modify 115 the action of said electro-responsive means.
- 120 9. The combination with a feeder circuit and an induction type regulator therefor, of a reversible motor for adjusting the position of the movable element of said regulator and thereby adjusting the voltage on said feeder circuit, an alternating current supply circuit for said motor independent of said feeder circuit, electromagnetic reversing means for said motor, a contact making voltmeter adapted to control said electromagnetic reversing means, said contact making voltmeter comprising stationary contacts, a movable contact adapted to coöperate therewith, electro-responsive means, responsive to a decrease in feeder voltage, for effecting the engagement of said movable 125 contact with one of said stationary contacts and, to an increase in feeder voltage, for effecting the engagement of said movable contact with another of said stationary contacts, a winding adapted to be connected to said independent alternating current supply circuit upon the engagement of said movable contact with the first mentioned stationary contact and tending, when so connected, to maintain such engagement, and a plurality 130 of windings oppositely wound with respect to the direction of the magnetic field developed by said electro-responsive means.

of windings oppositely wound with respect to the direction of the magnetic field set up by said electro-responsive means and adapted to be serially connected to said independent alternating current supply circuit upon the engagement of said movable contact with the second mentioned stationary contact, one of said windings tending, when so connected, to maintain engagement between said movable contact and the second mentioned stationary contact and the other of

said windings co-operating with and adapted to modify the action of said electro-responsive means, and means operative upon an abnormal decrease in the voltage of said feeder circuit for causing said motor to adjust the regulator for a minimum feeder voltage.

In witness whereof, I have hereunto set my hand this 28th day of February, 1917.

FRED H. WINTER.
